Primary Examiner — Ian Simmons*Assistant Examiner* — Shannon Morgan(74) *Attorney, Agent, or Firm* — Vidas, Arrett & Steinkraus, P.A.(57) **CLAIM**

The ornamental design for a roll top condiment tray, as shown and described.

DESCRIPTION

FIG. 1 is a top, left, front perspective view of a roll top condiment tray showing my new design.

FIG. 2 is a front elevation view thereof;

FIG. 3 is a bottom plan view thereof;

FIG. 4 is a rear elevation view thereof;

FIG. 5 is a top plan view thereof; and,

FIG. 6 is a right elevation view thereof.

The broken lines in FIG. 3 of the roll top condiment tray are for the purpose of illustrating environment, and form no part of the claimed design.
